UNITED STATES PATENT OFFICE.

CHARLES F. HUNT, OF WORCESTER, MASSACHUSETTS.

TWISTED AND FLATTENED WIRE BOX-FASTENING.

SPECIFICATION forming part of Letters Patent No. 352,246, dated November 9, 1886.

Application filed April 12, 1886. Serial No. 198,553. (Model.)

To all whom it may concern:

Be it known that I, CHARLES F. HUNT, of Worcester, in the county of Worcester and State of Massachusetts, a citizen of the United States, have invented a new and useful Improvement in Twisted-Wire Box-Fastening Straps, of which the following is a full, clear, and exact description, reference being had to the accompanying drawings, forming a part of this specification, in explaining its nature.

The object of the invention is to provide a twisted-wire box-fastening strap having holes placed closely together to provide holes always conveniently arranged for the reception of the fastening-nails.

It is very essential that box-fastening straps of this character should have a great many more holes than are actually necessary for use, in order that as many as may be necessary for use in receiving the nails employed in securing the fastening-strap to the box may be in proper position for use; and I have ascertained that it is possible to provide a twisted-wire box-fastening strap having a provision of this character and to obtain such provision in a cheap and economical way. The method that I employ is to take the strands of wire, twist the same, and then roll or flatten the twisted wires to open them and form a hole between each twist.

Referring to the drawings, Figure 1 is a plan view of two strands of wire twisted. Fig. 2 is a section on the line $x-x$ of Fig. 1. Fig. 3 is a section on the line $y-y$ of Fig. 1. Fig. 4 is a view in plan of a section of the strap. Fig. 5 is a section upon the line $x-x$ of Fig. 4. Fig. 6 is a section upon the line $y-y$ of Fig. 4. Fig. 7 illustrates in section a portion of a box, the strap, and a fastening-nail. Fig. 8 is a perspective view of a box to further illustrate the use of my invention, showing a strap at one end thereof.

In practicing my invention I take, preferably, two strands of wire, a a' , of the requisite size, and twist them to the desired extent, and after they have been thus twisted I submit them to the action of a rolling-machine or other device, whereby the twisted wire is flattened laterally and opened, so that nail-receiving

holes a^2 are formed between the two strands, 50 and of course as these holes are so closely placed to each other in the strap the holes must always be located where needed for the reception of the nails used in securing the fastening-strap to a box.

In the drawings I represent in Fig. 1 a plan of the strap before it is flattened, and in Fig. 4 a plan view after it has been flattened.

The extent to which the wire is twisted depends somewhat upon the size of the wire, its 50 quality, and also the purpose for which it is to be used and the size of the holes which it is desired to obtain. Of course tightly-twisted wires could not be rolled to produce openings between them for the reception of the fastening-nails. Ordinary iron wire twisted to a medium degree would upon rolling show a small but sufficient opening for conical-pointed wire nails, the kind now ordinarily used in the manufacture of boxes, which answer sufficiently well for use in connection with nails of this character. Wire loosely twisted will 65 of course when rolled show larger holes than that which is less loosely twisted; but I consider that my invention embraces a wire fastening-strap, however it may be twisted, whenever by rolling said twisted wire openings for the reception of points of the fastening-nails shall be provided. It will be seen, also, that by 70 submitting the twisted wire to the action of suitable rolls, which flatten the twist in rolling, a better form is provided the strap than if it were simply twisted, so that not only does the rolling of the twisted wire produce the openings or spaces for the reception of the points 75 of the fastening-nails, but it also forms the twisted wire into the best shape for a box-fastening.

Having thus fully described my invention, I claim and desire to secure by Letters Patent 90 of the United States—

A box-fastening strap consisting of twisted and flattened strands of wire, substantially as described.

CHARLES F. HUNT.
